(57) **CLAIM**

The ornamental design for a hydroponic plant container portion, as shown and described.

DESCRIPTION

FIG. 1 is a perspective view of the hydroponic plant container portion in full line;

FIG. 2 is a front elevational view thereof, the rear elevational view being a mirror image thereof;

FIG. 3 is a top plan view thereof; and,

FIG. 4 is a bottom plan view thereof.

The broken line showing of portions of the hydroponic plant container is for illustrative purposes only and forms no part of the claimed design.
